Primary Examiner — Keith J Wilson(57) **CLAIM**

The ornamental design for a hand pump, as shown and described.

DESCRIPTION

FIG. 1 is a perspective view of a hand pump according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the hand pump according to my new design which take off the upper cover; and,

FIG. 9 is a cross-sectional view from 9-9 line of FIG. 6.

The broken lines are included for the purpose of illustrating portions of the hand pump that form no part of the claimed design.

1 Claim, 9 Drawing Sheets(56)
